TOOL CONTAINER AND CUTTING BLOCK

Cyril T. Hofmeister, Oakland, Calif., assignor, by
mesne assignments, to Standard Oil Company
of California, San Francisco, Calif., a corpora-
tion of Delaware

Application May 3, 1933, Serial No. 669,091

6 Claims. (Cl. 164—78)

This invention relates to a portable tool container and cutting block, and particularly one adapted to hold tools of the punch or chisel type which are used for cutting sheet rubber and similar materials. The device is also adapted to be used as a block on which the material may be placed while the punches are being driven therethrough.

For example, when cutting a floor mat for an automobile from a roll of sheet rubber composition, or a "universal" blank mat, there are a number of openings which must be provided, for gear shift and brake levers, starter and throttle buttons, brake pedals, etc. These openings may conveniently be cut by a hollow punch of suitable size and shape, or by a suitable chisel. In punching or cutting the sheet material, it must first be laid on a firm support and the tool driven through it into the support, thus shearing out the part to be removed. This operation is most conveniently done in or near the automobile into which the mat is to be fitted. Under ordinary circumstances there are no stable and suitable supports either in the car or near it, into which a punch or chisel could be driven, without marring the support, or seriously damaging the cutting edge of the tool.

It is an object of this invention to provide a portable holder for tools such as punches, chisels, and the like, which holder is also adapted to act as a cutting block for supporting the material to be worked upon.

Another object is to provide a portable holder in which the tool receptacles are arranged to retain the tools against falling out when the holder is carried or is in position to be used.

Another object is to provide a combined holder and cutting block for tools such as punches and chisels, which are to be used at a point remote from a work bench or shop, and where work must be done quickly with a minimum of measuring and fitting.

These and other objects and advantages of this invention will become apparent from the following detailed description, and from the accompanying drawing, which forms a part of this specification, and illustrates a preferred embodiment of the invention.

In the drawing:

Figure 1 is a plan of a holder block made of wood and embodying this invention, with various punches and cutting chisels in place ready to be carried to the work.

Figure 2 is a side view of the holder block shown in Figure 1 and is partly sectioned as indicated

along the line II—II of Figure 1 to illustrate a method of providing tool holding recesses or receptacles in the block.

Figure 3 is an end view of the holder block shown in Figure 1 and shows the working or cutting face on which the material is cut or punched.

Referring to the drawing, the body of the holder block is generally designated 10, and may be made from a hard wood or a material which is sufficiently strong and heavy to furnish an adequate support for the punching and cutting operation; which is not too heavy or bulky to be portable; and which has one face soft enough so that the sharp cutting edges of the tools will not be dulled when they are hammered through the material worked upon and into the block. For example, a skeleton metal frame with one soft face of leather or the like obviously could be substituted for the construction shown.

The six faces of the block illustrated are designated as shown; 11 being the top, 12 the bottom (when the holder is upright, as illustrated), 13 and 14 the sides, and 15 and 16 the ends, the latter preferably being the end grain of the block, when the latter is made of wood.

A handle 17 is attached to the top 11 of the block near the edge of face 16, as shown, so that when the block is supported by the handle, as in carrying, the face 15 will swing downwardly, leaving the block tilted, for a purpose which will be explained presently.

Receptacles 18 are formed in the top 11 of the block 10, as shown, these receptacles being bored at an angle to the face and inclined toward the handle 17. Thus, when the block is lifted by the handle 17 and the block tilts to bring its center of gravity immediately below the handle, the tools, punches and the like, generally designated 19, will not fall out and be misplaced or lost. Furthermore, when the block 10 is placed in its working position, with its face 15 at the bottom, the tools 19 will likewise be held, by the inclination of receptacles 18, against falling out due to the jarring of the cutting and punching operations on cutting face 16.

Tools 19 may be of the conventional type, with a hardwood handle or striking piece 20 and a tubular steel cutter 21, the lower edge being sharpened as at 22. Groove 27 allows punched material to be removed by a wire or rod inserted from outside the tool.

In addition to, or in place of, the receptacles 18, formed in the body of the block 10, straps 23 may be attached to the faces 13 or 14 to provide receptacles for tools such as the side cutter 55

or chisel generally designated 24. These straps also are preferably inclined at an angle with regard to the top face 11 of block 10, and slope the tools toward handle 17, for the same reason as explained above for receptacles 18. Chisel 24 may be of any desired construction, the example shown being made with an angle steel blade 25, to which is secured a handle 26.

In operation, the holder block 10 with its tools 10 19 and 24 in place, may be carried to the automobile or other point of use, without danger of losing or injuring the tools. The block may then be laid on any suitable surface, such as the car floor or running board or on the ground, with 15 the face 15 at the bottom. Tools 19 and 24 are then readily accessible for use and replacement, and may be utilized to punch or cut a sheet of material, such as a rubber floor mat, which is placed on the cutting face 18. Tools 19 may 20 be of such nature that they may be used by pressure alone, or they may be forced through the material by hammer blows. When they are thus forced through into the face 16 of block 10, the wood or other relatively soft material will 25 not injure the sharp cutting edges, nor will the inclined receptacles 18 and 23 allow the tools not being used to fall out, to be lost, or to cause injury or damage.

From this description and drawing, it will be 30 seen that an improved portable tool holder and cutting block has been disclosed, which provides storage and carrying receptacles for tools, and also furnishes a substantial and rigid cutting face, on which the material to be operated on 35 is supported and into which the sharp edged tools may be driven.

Although a specific construction embodying this invention has been described and illustrated, it is to be understood that the invention is not 40 limited to that arrangement, and all such modifications and changes as come within the scope of the appended claims are embraced thereby.

I claim:

1. A portable cutting block for edged tools 45 comprising a block of material substantially softer

than a tool edge, a plane cutting face on said block, and tool receptacles in the body of said block, said receptacles having their axes inclined with regard to a face of said block and sloping toward the plane of said cutting face.

2. A portable container and cutting block for edged tools, comprising a block, one face of which is substantially softer than a tool edge and forms a cutting surface, receptacles for tools associated with said block, and a handle for said block, said 10 receptacles having their axes inclined above the horizontal when the block is supported by said handle and also when said cutting face is in a position to be used.

3. A portable container and cutting block for 15 edged tools comprising a block, one face of which is substantially softer than a tool edge, receptacles for tools associated with said block, and a handle for said block near one edge thereof, said 20 receptacles being at an angle to one face of said block and sloping toward said handle.

4. A portable container and cutting block for 25 edged tools comprising a wooden block, a cutting face on said block, a receptacle for a tool bored into said block at an angle to one face thereof, and a handle on said face adjacent that edge toward which the receptacle is inclined, whereby 30 the axis of said receptacle is inclined above the horizontal while said block is supported by said handle.

5. A portable container and cutting block for 35 edged tools comprising a block, one face of said block being substantially soft and forming a plane cutting surface, a receptacle for a tool associated with said block and inclined toward the plane of 40 said cutting surface, and a handle on said block adjacent one edge of said cutting surface.

6. A portable container and cutting block for 45 edged tools comprising a block, one face of said block being substantially soft and forming a plane cutting surface, and a receptacle for a tool associated with said block and inclined toward the plane of 50 said cutting surface.
